ELECTRICAL CONNECTER

Filed June 29, 1937

A hand-drawn technical sketch of a device labeled "Fig. 1." The drawing shows a central vertical component labeled 10, which has a cylindrical part labeled 23 at the top. This central part is mounted on a rectangular base labeled 11. The base has several features: a slot labeled 21 on the left side, a circular hole labeled 19 on the right side, and two circular holes labeled 27 on the front face. A horizontal bar labeled 26 is shown extending from the left side of the base. The entire sketch is done in black ink on a white background.

ELECTRICAL CONNECTER

Ralph August Toelke, Cincinnati, Ohio

Application June 29, 1937, Serial No. 151,033

1 Claim. (Cl. 173—340)

This invention relates to electrical connectors and has for an object to provide a device of this character which may be substituted for conventional outlet boxes in wiring systems, and which will be formed of a few strong simple and durable parts, which will be inexpensive to manufacture, and which will not easily get out of order.

With the above and other objects in view the invention consists of certain novel details of construction and combinations of parts hereininafter fully described and claimed, it being understood that various modifications may be resorted to within the scope of the appended claim without departing from the spirit or sacrificing any of the advantages of the invention.

In the accompanying drawing forming part of this specification,

Figure 1 is a perspective view of an electrical connector constructed in accordance with the invention.

Figure 2 is a plan view of the electrical connector with the cover removed.

Figure 3 is a longitudinal sectional view of the electrical connector.

Referring now to the drawing in which like characters of reference designate similar parts in the various views, the electrical connector is shown to comprise a block 10 having a recess 11 opening through the front and lateral sides thereof. The block is provided with a socket 12 disposed perpendicular to the recess and opening through one end of the block.

Stationary pins 13 and 14 are imbedded in the block and project from the bottom wall of the recess 11. Set screws 15 and 16 extend into the socket from opposite sides thereof, as best shown in Figure 3. The set screw 15 is electrically connected to the stationary pin 13 by a conductor wire 17. The set screw 16 is electrically connected to the stationary pin 14 by a conductor wire 18.

A cover 19 for the block is provided with a projection 20 which enters the recess 11 and clamps a cable 21 in the recess. The stationary pins penetrate the insulation of the cable and engage the conductors 22 of the cable. The service

cable 23 is engaged in the socket 12 and the conductors 24 of the cable are engaged by the set screws 15 and 16.

The block is secured in place by screws 25 passed therethrough and into the walls 26. The cover is secured to the block by set screws 27.

When applying the electrical connector the service cable 23 may be inserted in the socket 12 and the set screws 15 and 16 tightened to penetrate the insulation thereof and engage the conductors 24. The block may now be secured in place by the screws 25. The outlet cable 21 may now be trained through the opening 11. The cover 20 is then applied and secured in place by tightening the screws 27 during which operation the insulation of the cable 21 is penetrated by the screws 13 and 14 which latter engage the conductors 22 of the cable and through the instrumentality of the conductor wires 14 and 17, electrically connect the outlet cable to the service cable.

From the above description it is thought that the construction and operation of the invention will be fully understood without further explanation.

What is claimed is:

An electrical connector comprising a block having a recess opening through the front and lateral sides thereof, there being a socket disposed in the block perpendicular to the recess and opening through one end of the block, stationary pins in the block projecting from the bottom wall of the recess, set screws extending into the socket from opposite sides thereof, a conductor electrically connecting one of the set screws with one of the pins, a conductor electrically connecting the other set screw with the other pin, said socket being adapted to receive a cable, said set screws being adapted to engage the conductors of the cable and electrically connect them with the pins, and a cover for the block provided with a projection adapted to enter the recess and clamp a cable in the block with the pins penetrating the insulation of the cable and engaging the conductors of the cable.

RALPH A. TOELKE.
